UNITED STATES PATENT OFFICE.

HENRY ROBERTS, OF PITTSBURG, PENNSYLVANIA.

FENCE-MACHINE.

955,907.

Specification of Letters Patent. Patented Apr. 26, 1910.

Application filed October 26, 1909. Serial No. 524,855.

To all whom it may concern:

Be it known that I, HENRY ROBERTS, of Pittsburgh, in the county of Allegheny, State of Pennsylvania, have invented a certain new and useful Improvement in Fence-Machines, of which the following is a full, clear, and exact description, reference being had to the accompanying drawings, forming part of this specification!

- 10 The object of my invention is to provide apparatus for weaving wire fencing and the like, and it consists in the combination and arrangement of parts as will be hereinafter more fully set forth.
- 15 I will now describe, referring to the accompanying drawings, my invention, so that others skilled in the art to which it appertains, may understand and construct the same.
- 20 In the accompanying drawings illustrating my invention, Figure 1 is a top plan view; Fig. 2 is a longitudinal sectional view on the line 2--2 of Fig. 1; Figs. 3 and 4 are enlarged longitudinal vertical sectional views showing the heddle for forming the shed in the longitudinal strands, mechanism for crimping said strands, and mechanism for laterally shifting the transverse strands or stay wires; Fig. 5 is a longitudinal vertical sectional view through the rolls for crimping the longitudinal strands; Fig. 6 is an elevation of the rotary heddle; Fig. 7 is an enlarged sectional view taken on the line 7--7 of Fig. 1 and showing mechanism for twisting or wrapping the ends of the transverse strands or stay wires around the two side longitudinal strands or running wires; Figs. 7^a, 8, and 9 are enlarged side elevations of the transverse strand or stay wire twisting mechanism, and showing the same in normal, advanced, and reversed positions, respectively; Fig. 10 is a top plan view of the same; Fig. 11 is a transverse section taken through the collar 25; Figs. 12 and 12^a are sectional views of the rotatory transverse strand or stay wire twisting head; and Fig. 13 is a fragmentary perspective view of the fencing which may be woven by my improved apparatus.
- 40 The strands 2 adapted to form the longitudinal or running wires of the fabric, are adapted to be fed from suitable reels 3 mounted at one end of the frame-work 4,

by means of the feed rolls 5 journaled at the opposite end of the frame-work in suitable bearings 6, and which are adapted to operatively engage with the fence fabric. These rolls 5 are operatively connected to the horizontal shaft 6^a which may be driven in any suitable manner. As the strands 2 pass from the reels 3 they are adapted to receive the crimps *a* which project alternately in diametrically opposite directions; which crimps are adapted to interlockingly engage with similarly formed crimps *b* of the transverse or stay-wires 2^a. This crimping of the strands 2 is accomplished by means of the rolls 7 which are provided with the crimping surfaces 8, which are provided with suitable alternately disposed crimping projections and recesses, and between which the strands are passed, while the crimps *b* are imparted to the stay-wires by means of the similarly constructed rolls 9. The rolls 7 may be operatively connected to the shaft 6^a. The stay-wire is carried by the suitable reel 10, from which it is caused to be drawn through suitable straightening and shearing mechanisms 11 and 12, respectively, and fed to the running wires by means of the rolls 9. This shearing mechanism and the rolls 9 may be operatively connected to any suitable source of power. And in order to present a straight wire to the shearing mechanism, I mount this shearing mechanism intermediate the straightening mechanism and the crimping and feeding rolls.

Journalized in suitable bearings 13 is the horizontal shaft 14 provided with the series of eccentrically mounted peripherally-grooved disks 15 which are alternately, diametrically, oppositely disposed (see Figs. 1, 3, and 4). Over these disks the strands 2 are adapted to be threaded, being received by the peripheral grooves 16. With a shifting of the position of the disks 15 by a rotation of the shaft 14 the longitudinal strands or running wires 2 are caused to be alternately, oppositely, vertically shifted so as to separate and form an opening *c* between the strands for the reception of a transverse or stay-wire. This opening is known in the art as a shed, and its formation is clearly shown in Figs. 3 and 4; in Fig. 3 the series *d* of longitudinal strands forming the top of the opening or shed,

while the bottom or lower series is indicated by the letter *e*. A shifting of the position of the eccentrically disposed disks 15 will cause a reversal of the position of the series 5 *d* and *e* with the consequent binding of a stay-wire within a shed and the formation of another shed for the reception of another stay-wire, as shown in Fig. 4.

Journalized in suitable bearings 17, forward of the table 18 over which the fabric is adapted to be drawn by the rolls 5, is the horizontal shaft 19, provided with the radial arms or fingers 20 which, in the rotation of the shaft 19, are caused to sweep around in 15 a vertical plane between the strands 2 and laterally shift the stay-wire into engagement with the crimps of the longitudinal or running wires, after the stay-wire has been fed into the shed or opening between 20 the running wires. The operation of this stay-wire shifting mechanism is clearly shown in Figs. 3 and 4; Fig. 3 showing the fingers 20 advancing to shift the stay-wire 2^a and Fig. 4 showing the fingers as shifting 25 the stay-wire into position simultaneously with the formation of another shed for the reception of another stay-wire.

Means for wrapping or twisting each end of the stay-wire, around its respective running side-wire, are mounted at each side of the table 18 and each comprises the twister head 21 carried by the support 22 which in turn is carried by the shaft 23 mounted in the bearings 24 between which and splined 35 to the shaft 23 is the collar 25, which collar is provided with the gear face 26 which meshes with the segment 27 pivoted to the depending bearings 28. This segment is adapted to be rocked by means of the cam 29 40 which is operatively connected to the segment by the depending arm 30. The purpose of this collar and segment arrangement is to cause a rocking of the shaft 23 for a reversal of the position of the support 22 45 for the purpose set forth below. The cam 29 is carried by the horizontal shaft 31 journalized in suitable bearings 32 and which may be driven in any suitable manner. Lying parallel to this shaft 31 is the shaft 33 50 journalized in the bearings 34 and which by means of suitable bevel gearing 35 is operatively connected to the cam 36. This cam 36 is adapted, through the intermediary of the double arm lever 37, to cause a reciprocation of the shaft 23 in the bearings 24. To permit of a rotation of the shaft 23 while still maintaining operative connection with the rocker arm 37, this arm is provided with the fork 38 which embraces 55 the collar 39 loosely carried in an annular seat in the shaft 23, which collar carries the suitable studs or rollers 40 by means of which the fork 38 operatively engages with the collar 39.

The construction and operation of the 65 twister head 21 will be readily understood by referring to Figs. 7^a, 8, 9, and 10. The head is provided with the fingers 41 which are adapted to overhang the running wire on each side of the stay-wire, when the head 70 has been caused to be shifted into engagement with the said wires, as shown in Fig. 7^a. And in such advance and engagement with the wires, the end 42 of the stay-wire is caused to enter the space or opening between the fingers 41, lying along the shoulder 43 which is adapted, when the head is caused to be rotated, to twist or wrap the end of the stay-wire around the strand 2 lying within the radial recess 43' which is 80 formed by the overhanging fingers 41 and the parallel extending shoulder or face 43. The rotation of the twister head is accomplished by means of the rack face 44 carried by the arms 45 between which the head 21 85 is mounted. This rack is adapted to mesh with the pinions 46 carried by the head 21 and which are adapted to travel in the ways 47 in the arms 45. The rotation of the head 21 is effected by the forward travel of the 90 support 22 after operating to bring the head 21 into the operative position shown in Fig. 7^a. As will be seen in Fig. 7^a the head 21 will be prevented by reason of its engagement with the edge running wire 2, from 95 further advancing with the support 22 after the head has been brought to the position shown, and the continued forward movement of the support 22 will cause the rack face 44 to act on the pinions 46 of the head 100 thereby causing the head 21 to be rotated around the strand 2, as shown in Fig. 8; such rotation of the head 21 causing the end 42 of the stay-wire to be folded over or wrapped around the longitudinal strand 2 105 by reason of the shifting of the wrapping shoulder or face 43 against which the stay-wire end 42 is adapted to rest, as described above. And means for supporting the strand 2 against lateral shifting, when the head 110 21 is caused to be brought into engagement therewith in the above described manner, comprises the projecting face or shoulder 48 carried by the table 18 and against which the strand 2 is adapted to bear in the forward travel of the support 22. After operating and twisting the stay end in the manner above set forth, a reverse shifting or return travel of the support 22 will cause the rack faces of the support 22 to act on 115 the pinions of the head 21 in a reverse direction, with a consequent return of the head 21 to normal position.

If, in the weaving of the fabric, the formation of the sheds is such as shall cause 12 the stay-wires to assume a position in alternation on opposite sides of each side or edge running wire as shown in Fig. 18, to

effect a twisting or wrapping of the end of the stay-wire around the edge running wire, when the stay-wire is caused to be fed over instead of under the running wire, as shown in Fig. 9, it is necessary that the twister head 21, when advanced by the support 22 into engagement with the strands, as above described, be caused to rotate in a reverse direction as indicated by the arrow in Fig. 9. This is accomplished by giving the support 22 a one-half revolution so as to reverse the position of the head 21 as is clearly shown in Fig. 9. This rocking or turning of the support 22 is adapted to take place when the support has been retracted to normal position; the collar, segment and cam arrangement for causing this rotation of the support being described above.

From the foregoing description, the operation of the apparatus will be readily understood. The feeding of the fabric should be intermittent so as to enable the stay-wires to be momentarily held for the advancement of the edge twisting mechanisms.

It will be apparent that many changes may be made in the different mechanisms without departing from my invention.

The advantages of my invention will be found to reside in the simplicity of the different mechanisms and their effectiveness.

Having thus described my invention what I claim and desire to secure by Letters Patent is—

1. In an apparatus of the character described, the combination of mechanism for feeding the warp strands, means for crimping the warp strands, a heddle, mechanism for feeding weft strands to the warp strands, and means for laterally shifting the weft strands into engagement with the crimps of the warp strands.

2. In an apparatus of the character described, the combination of mechanism for feeding the warp strands, means for crimping the warp strands, a heddle, mechanism for crimping and feeding weft strands to the warp strands, and means for laterally shifting the weft strands into engagement with the crimps of the warp strands.

3. In an apparatus of the character described, the combination of mechanism for feeding and means for crimping the warp strands, a heddle, mechanism for feeding weft strands to the warp strands, means for laterally shifting the weft strands into engagement with the crimps of the warp strands, and means for twisting the ends of the weft strands around the edge warp strands.

4. In an apparatus of the character described, the combination of mechanism for feeding and means for crimping the warp strands, a heddle, mechanism for crimping and feeding weft strands to the warp

strands, means for laterally shifting the weft strands into engagement with the crimps of the warp strands, and means for twisting the ends of the weft strands around the edge warp strands.

5. In an apparatus of the character described, the combination of a support, a twister head carried thereby, means for reciprocating the support so as to bring the twister head into and out of operative position, and means whereby the reciprocation of the support is adapted to cause a rotation of the twister head.

6. In an apparatus of the character described, the combination of a support, a twister head carried thereby, means for shifting the support so as to bring the twister head into and out of operative position, and means for rotating the twister head, comprising a toothed face carried by the support and adapted to mesh with a toothed face on the twister head.

7. In an apparatus of the character described, the combination of a support, a twister head carried thereby, means for rotating the twister head, means for advancing the head to operative position for a rotation thereof in one direction, and means for advancing the head to operative position in a reverse position for a rotation in an opposite direction.

8. In an apparatus of the character described, the combination of a support, a twister head carried thereby, means for rotating the twister head, means for shifting the support so as to bring the twister head into and out of operative position, and means for reversing the support so as to cause the twister head, after advancing to operate in one direction, to be reversed so as to cause it when again advanced to operate in an opposite direction.

9. In an apparatus of the character described, the combination of a support, a twister head carried thereby, means for shifting the support so as to bring the twister head into and out of operative position, means carried by the support whereby the twister head is caused to be operatively rotated when the support is caused to be advanced, and means for causing the support to be reversed intermittently whereby the twister head will be caused to be advanced to rotate alternately in opposite directions.

10. In an apparatus of the character described, the combination of a support, a twister head carried thereby, means for shifting the support so as to bring the twister head into and out of operative position, means for rotating the head, comprising a toothed face carried by the support and adapted to mesh with a toothed face carried by the twister head, and means for reversing the support for a reversal of the

direction of the rotation of the twister head when caused to be rotated by the advance of the support.

11. In an apparatus of the character described, the combination of a support, a twister head carried thereby, means for shifting the support so as to bring the twister head into and out of operative position, means for rotating the twister head when it has been caused to be brought to

operative position, and means for preventing displacement of the longitudinal strand when the twister head has been caused to be brought into engagement therewith.

In testimony whereof, I have hereunto set my hand.

HENRY ROBERTS.
